PUMP

Fred M. Cousins, Grosse Pointe Woods, and Harold L. Brock, Detroit, Mich., assignors to Ford Motor Company, Dearborn, Mich., a corporation of Delaware

Filed Aug. 24, 1956, Ser. No. 606,118

3 Claims. (Cl. 74—60)

This invention relates to pumps, and more specifically to a hydraulic pump in which one or more individual pistons are driven by a so-called "swash plate."

The pump of the present invention, which is particularly useful in the pumping of hydraulic fluids, consists of a pump body having one or more planetarily arranged, nonrotating cylinders each of which are provided with an inlet and outlet port and a piston which is spring-pressed in its return stroke. The pistons are successively driven in their pumping strokes by a swash or wobble plate whose surface extends in a plane non-radially of the drive shaft of the pump. Among the characteristics of this pump are economy of manufacture and extreme durability and long-life, even when pumping hydraulic fluids containing a relatively large amount of abrasive dirt and dust particles.

Among the objects of the present invention are to provide a pump for hydraulic fluids which is economical to manufacture, is durable and long-lived, and which will pump fluids containing a relatively large amount of abrasive dirt and dust particles without causing undue wear of the pump or otherwise affecting its operation.

Other objects and the nature and scope of the invention will become more apparent from a consideration of the detailed description to follow, taken in conjunction with the drawings.

Our invention is clearly defined in the appended claims. In the claims, as well as in the description, parts may at times be identified by specific names for clarity and convenience, but such nomenclature is to be understood as having the broadest meaning consistent with the context and with the concept of our invention as distinguished from the pertinent prior art. The best form in which we have contemplated applying our invention is illustrated in the accompanying drawings forming part of this specification in which:

Figure 1 is an axial section of the pump, certain of the parts of the pump being shown in side elevation.

Figure 2 is an enlarged fragmentary section of the pump, showing a portion of one of the cylinders, together with its intake and outlet valve and a portion of its piston.

Figure 3 is a somewhat diagrammatic enlarged fragmentary section showing the contact between the end of one of the pistons and the swash plate.

Referring now to Figure 1, the pump of the present invention comprises a pump body 10 which may consist of a two-part casting, one part 11 of the body having one or more planetarily arranged cylinders extending parallel to a central axis and preferably also including an inlet manifold 12 communicating with each of the cylinders. The second part 14 of the pump body rotatably mounts a drive shaft 15, which will be described hereinafter. An outlet manifold 16 may be secured to an end of the pump body part 11 to close the ends of the cylinders and to mount the outlet valve for each cylinder, as will be described.

Referring now more specifically to the pump body part 11, this part has one or more cylinders 19 formed therein

2

which are parallel to and equally spaced from a central axis 20 of the pump body 10. Each cylinder 19 has a bore 21 extending from an enlarged, axially centered chamber 22 communicating with all of the cylinders 19 and receiving the end of the drive shaft 15. The end 24 of each cylinder 19 adjacent the outlet manifold 16 is of slightly larger diameter (preferably about fifteen thousandths of an inch larger) and is on a common axis with the bore 21 to provide a step or ledge 25 for wiping and accumulating abrasive particles from the side bearing surface of a piston 26 positioned within the cylinder.

The inlet manifold 12 is preferably cast integrally with the pump body part 10 and completely surrounds the cylinders 19. The inlet manifold 12 may be provided with a flange 29 surrounding the entrance to the manifold, the flange 29 being provided with a groove 30 to retain an O ring (not shown). Preferably the manifold 12 is cast with a hole 180° from the flange 29 to aid in removing the core sand, the hole subsequently being closed with a plug 27.

A series of inlet ports 31 are provided, one for each cylinder, connecting the manifold 12 with the cylinders 19. Each inlet port 31 is provided with an inlet valve which is preferably of the check-valve type consisting of a steel sphere or ball 34 spring-pressed by a spring 35 into sealing engagement with a ring-shaped valve seat 36. Preferably, the inlet valves are received within a space disposed radially outwardly of the cylinders 19 and communicating therewith, as indicated in the drawings.

The outlet manifold 16 preferably comprises an end casting bolted to the end of the pump body part 11 and having an annular passage 37 extending opposite the ends of the cylinders 19. A flange 39 surrounding the outlet passage 37 and preferably coplanar with the inlet flange 29 and provided with a gasket groove 40 provides a leak-tight connection for the outlet passage. Studs 41 may be provided for holding the flanges 29 and 39 in sealing relation to hydraulic conduits (not shown) leading to and from the pump body 10.

An outlet port 42 connects each cylinder 19 with the outlet manifold passage 37. Preferably, each outlet port 42 extends axially from the end of a cylinder 19. Each port 42 is provided with an outlet valve of the check-valve type, consisting of a steel ball 45 which is biased into seating engagement by a spring 46. Preferably, the springs 46 are supported against displacement by pilot pins 47.

For convenience of manufacture, and for easy replacement of the valve seats of the outlet valves 44, the valve seats and outlet ports 42 are formed within a flat plate 49 which may be secured to the outlet manifold 16 by a screw 50 located axially of the pump. The plate 49 seals the ends of the cylinders 19, gaskets being interposed between the plate, the pump body part 11 and the manifold casting 16. The plate 49 also has pins 48 mounted therein for supporting the inlet springs 35 against displacement.

Each piston 26, adjacent the enlarged, pumping end 24 of the cylinder, has an end portion 51 of reduced diameter to provide clearance for a helical piston spring 52 extending between the plate 49 surrounding the outlet port 42 and the portion of the piston fitting within the bore 21 of each cylinder. The springs 52 serve to return the pistons in their suction stroke, at which time the outlet valve 44 is closed and fluid is drawn in through the inlet valve 32, displacing the ball 34 from its seat. Preferably, each piston spring 52 is maintained axially centered within the enlarged end 24 of the cylinder and out of contact with the end portion 51 of the piston by a concentric stepped portion 54 of the piston of diameter

intermediate between that of the end portion and the maximum diameter of the piston.

The pistons 26 are operated by rotation of the drive shaft 15 which extends axially of the pump. The drive shaft 15 comprises a shaft extending axially of the pump and received principally within the portion 14 of the pump body. The drive shaft 15 is supported for rotation within the pump body portion 14 by a tapered roller bearing 55 capable of supporting both radial and axial loads and a needle bearing 58. The end of the drive shaft 15 towards the pistons 26 is formed to provide a flat circular plate or surface 56 extending nonradially thereof and received within the chamber 22. The surface 56 of the shaft is provided with a cylindrical central portion 57 projecting perpendicularly to the surface 56 and retaining a circular swash plate 59 separated from the surface 56 of the shaft by a thrust bearing 60 of the roller type. The construction is such that the plate 59 is free to turn on the surface 56 of the shaft 15 and is maintained centered on such surface by the projecting portion 57 of the shaft. The surface 61 of the plate 59 is concentric with the axis of the drive shaft 15 but extends nonradially thereof, the assembly of drive shaft and plate forming a swash plate drive for operating the pistons 26.

The amount which each piston is reciprocated by the plate 59 depends upon the degree of angularity of the plane of the plate 59 to the axis of the drive shaft 15, and also upon the distance from the axis of the drive shaft to the point of contact between the plate and piston. The pump shown herein is of the fixed displacement type, the angularity of the plate 59 being fixed and the point of contact between the plate and the pistons being a fixed distance from the axis of shaft 15.

The piston springs 52 bias the pistons towards the surface 61 of the plate 59 so that the pistons tend to follow the plate during the suction stroke of each piston and are driven by the plate during their pumping stroke. Although the drive shaft 15 is rotated at a relatively high speed, e.g., up to 2000 r.p.m. or greater, there is essentially no rotation of the plate 59 against the pistons 26, this plate having instead a rolling or nutating motion about the ends of the pistons. In fact, the plate 59 will rotate very slowly in the opposite direction, which serves to distribute wear evenly on the piston-contacting surface of the plate.

In order to assure long pump life, even when pumping hydraulic fluids containing substantial amounts of abrasive particles and operating at pressures of 2000 p.s.i. or more, the ends of the pistons are given a specific contour which is shown in more detail in Figure 3. The end of each piston 26 has a convexly arched surface of rotation 62, the amount of arch or crown of the surface being about .002 of an inch. The surface of rotation 62 closely approximates a truncated cone, the elements of which make an angle with the axis of the piston equal to the angle between the surface 61 of the plate 59 and the axis of the drive shaft 15 (about 11½ degrees in the present pump).

Preferably, each piston 26 is provided with a marginal chamfer 64 surrounding the surface 62 and a central flat 65. The piston contour is such that as the drive shaft 15 is rotated, the plate 59 will make rolling contact with the surface 62 of each piston, the contact occurring over an area C intermediate the inner and outer diameters of the surface 62 and preferably a little closer to the outer diameter of such surface. The above-described contour of the ends of pistons 26 prevents contact over a small area adjacent either the center or the periphery of the pistons, even despite minor misalignment of portions of the pump due to normal manufacturing tolerances and construction of the pump body in two pieces, and thus contributes to long life of the pump.

The drive shaft 15 is provided with a smooth, cylindri-

cal surface 66 for receiving a shaft seal 67 to prevent passage of hydraulic fluid along the shaft. However, the circular chamber 22 which contains the plate 59 is vented to the inlet manifold 27 by one or more holes 69 so that any leakage that may occur past the pistons 26 will feed back into the inlet manifold rather than force its way past the shaft seal, and the maximum hydraulic pressure on the shaft seal will be the pressure in the inlet manifold. The needle bearing 58 also engages the surface 66.

The end 70 of the drive shaft 15 may be splined or keyed if desired to receive a drive gear 71 which may project through an opening 72 in the side of the pump body part 14. The drive gear 71 may be held on the shaft 15 by a screw 74 and washer 75, the screw being provided, if desired, with a slotted head for reception of a tachometer drive assembly 76 screwed into the end of the pump body part 14.

Preferably, the inlet valve springs 35 are somewhat weaker than the outlet valve springs 46, as indicated in the drawings, to assure prompt and complete opening of the inlet valves 32 and complete filling of the cylinders 19 during the suction stroke of the pistons. The outlet valve springs 46 are made heavier to assure prompt closing of the valves after pumping strokes of the pistons are complete. The piston springs 52 normally are made sufficiently strong to maintain the ends of the pistons against the swash plate 59 at all times.

For some purposes, e.g., power steering of vehicles, it is desirable to have a pump that will provide a more or less uniform volume of output over a substantial speed range. The pump of the present invention is particularly adaptable for such a purpose by placing a restricted orifice or choke 77 in the inlet manifold 12 to restrict the flow of fluid to the pump. The piston springs 52 may be chosen of such strength that, at lower rotative speeds of the pump, the ends of the pistons will follow the swash plate 59 during its entire cycle of rotation. However, at higher speeds the choke 77 will starve the cylinders 19, the pistons following the swash plate 59 for only a portion of its cycle and thus pumping less than their full volume. The nutative movement of the plate 59 will permit it to reengage the ends of the pistons 26 without undue shock and vibration.

The above-described pump is simple and economical to manufacture and at the same time is efficient and dependable in operation. The unswept volume of each cylinder is slight, making the pump self-priming under most circumstances. The pump body 10 is formed of two pieces for ease and economy of manufacture, and minor inaccuracies of alignment resolving from normal tolerances and the two piece body are compensated for by the specific contour of the piston ends, thus providing a pump in which wear is reduced to the minimum, thus assuring long life and dependable operation.

We claim:

1. In a pump for hydraulic fluids of the type in which pistons operating in parallel cylinders within a first pump body portion are operated in their pumping stroke by a drive shaft journaled in a second pump body portion and carrying a nonradially extending flat plate portion positioned opposite the ends of the cylinders, the pump body portions being united, the improvement which comprises: the plate-portion-contacting end of each piston being shaped to provide a convexly arched surface of rotation closely approximating the surface of a truncated cone, the elements of which make an angle with the axis of the piston corresponding to the angle between the plane of the plate portion of the drive shaft and its axis, the arch of said surface of rotation being crowned on the order of a few thousandths of an inch whereby the zone of contact between the plate portion and the ends of the pistons will fall within the boundaries of the surface of

rotation despite minor misalignment between the first and the second pump body portions.

2. In a pump for hydraulic fluids of the type in which pistons operating in parallel cylinders within a first pump body portion are operated in their pumping stroke by a drive shaft journalled in a second pump body portion and carrying a nonradially extending flat plate portion positioned opposite the ends of the cylinders, the pump body portions being united, the improvement which comprises: the plate-portion-contacting end of each piston having the same diameter as the portion of the piston within the cylinder, having a peripheral chamfer and being shaped to provide a convexly arched surface of rotation closely approximating the surface of a truncated cone, the elements of which make an angle with the axis of the piston corresponding to the angle between the plane of the plate portion of the drive shaft and its axis, the arch of said surface of rotation being crowned on the order of a few thousandths of an inch whereby the zone of contact between the plate portion and the ends of the pistons will fall within the boundaries of the surface of rotation despite minor misalignment between the first and the second pump body portions.

3. In a pump for hydraulic fluids of the type in which pistons operating in parallel cylinders within a first pump

5
